(57) **CLAIM**

The ornamental design for a foldable solar charger, as shown and described.

DESCRIPTION

FIG. 1 is a front, bottom perspective view of a foldable solar charger, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 2; and,

FIG. 10 is another perspective view of the foldable solar charger, shown in a folded position.

The dashed broken lines in the figures illustrate portions of the foldable solar charger that form no part of the claimed design. The dash dot dash broken lines in FIGS. 2 and 9 are for the purpose of illustrating the enlarged view indicators and form no part of the claimed design.
